MACHINE FOR USE IN MAKING SHOE UPPERS

Filed Nov. 22, 1921

4 Inventor:
Alfred W. Donovan
by Arthur F. Randall
Atty.

UNITED STATES PATENT OFFICE.

ALFRED W. DONOVAN, OF ROCKLAND, MASSACHUSETTS.

MACHINE FOR USE IN MAKING SHOE UPPERS.

Application filed November 22, 1921. Serial No. 516,978.

To all whom it may concern:

Be it known that I, ALFRED W. DONOVAN, a citizen of the United States, residing at Rockland, in the county of Plymouth and 5 State of Massachusetts, have invented certain new and useful Improvements in Machines for Use in Making Shoe Uppers, of which the following is a specification.

This invention relates to the manufacture of boots and shoes and it has for its 10 object to enable shoe manufacturers to produce better fitting and better appearing shoe uppers than heretofore.

Heretofore, the methods and means employed in assembling and shaping the outside of the top and the lining of shoe uppers did not insure a correct shape and fit 15 so far as the proper relative positioning or fitting of those parts together was concerned, and as a result either the lining or the outside of the upper frequently presented a wrinkled and mis-shapen appearance in use. Moreover, the improper assembling and uniting of the top and lining 20 characteristic of the methods and means heretofore employed not only prevented proper fitting of the vamp to the top but also prevented the proper fitting of both the lining and outside of the finished upper 25 to the last.

My invention aims to obviate these objectionable features and to make it possible to conveniently, expeditiously and correctly assemble and shape shoe tops and linings 30 so that they may be accurately fitted, one to the other.

To these ends the invention consists first, in a new and useful machine for use in assembling and shaping the parts of a boot 35 or shoe upper, said machine having the peculiar features of construction and mode of operation hereinafter pointed out, and second, in a new method of making boot and shoe uppers.

In the accompanying drawings:

Figure 1 is a side elevation of my new machine for use in making boot and shoe uppers.

Figure 2 is a front elevation of the machine shown in Fig. 1.

Figure 3 is a perspective view of a partially completed shoe upper.

Figure 4 shows, in side elevation the two molding members hereinafter referred to

with a partially completed shoe upper in 55 position upon the male molding member.

Figure 5 is a front elevation of the parts shown in Figure 4.

Figure 6 is an enlarged detail of the upper portion of Figure 5.

Having reference to the drawings, particularly Fig. 3, 1 represents a shoe lining, 2, 2 the side facing strips, 3 the top facing strip and 4 the top, the lining usually being made of textile fabric and the facing pieces and top of leather. The usual practice, heretofore, has been to assemble these parts upon a flat surface such as the top 60 of a table and to secure them together while in this flat condition with the result that 65 the parts were inaccurately positioned relatively so that when the two sides of the upper were bent around alongside of each other as in Fig. 3, the lining upon the inside would be buckled and wrinkled and act 70 to so distort the top as to make it impossible to properly attach the quarter and vamp thereto.

Consequently, either the completed upper 75 would not properly conform to the last and 80 would be irregular and more or less out of shape or the lining upon the inside would be wrinkled and uncomfortable to the wearer of the shoe.

In proceeding in accordance with my invention the side facing strips 2 are fastened 85 to the lining 1 and then, the lining is bent around a V-shaped form 5 with the middle, or middle seam, of said lining extending along the ridge or apex thereof as shown 90 in Figs. 4 and 5 and 6, after which said lining is smoothed out by hand strokes and pressure or otherwise so as to remove all wrinkles. The top 4 is next placed in its proper position upon the lining while the latter remains upon form 5 and is smoothed 95 out by hand strokes and pressure, or otherwise, said top being secured to said lining by cement applied to one or the other, or both, of said parts previous to the application of said top to the lining, and being pressed firmly into position against the latter.

It is unnecessary to employ cement 105 throughout the area of the inner side of top 4, but it is desirable that it be used near the ends of the top and particularly between the back portion of the top and the back

portion of the lining to secure said parts together at that place so that during subsequent handling the rear portions of said parts retain their bent shape and do not 5 become separated or wrinkled.

After assembling the parts upon the V-shaped form 5 as above described a V-shaped iron preferably heated, is applied to the rear portion of the partly constructed upper 10 to fit the lining and top snugly around and against the apex of form 5 and to set the adjacent cement that is between the top and lining.

The machine herein shown which may be 15 used in practising the above described method comprises a stand or frame 7 provided at its top with a laterally extending arm 8 made at its outer end with a socket 9 to receive the shank 10 of iron 6, said shank 20 being secured rigidly within said socket by means of a set screw 11. Beneath the arm 8 is another laterally extending arm 12, within which is slidably mounted the stem or shank 13 of form 5. The lower end of 25 stem or shank 13 is pivotally connected as at 14 to one arm of a lever 15 fulcrumed at 16 on arm 12. The other arm of lever 15 is connected by a link 17 with a foot treadle 18 fulcrumed at 19 on standard 7. A spring 30 20 connected at one end to lever 18 and at its opposite end to standard 7 normally holds foot treadle 18 elevated with form 5 at the limit of its movement away from iron 6. After the parts of the upper are 35 assembled upon form 5 as above described, the operator depresses treadle 18 thereby lifting form 5 whose apex presses the rear portions of the upper into the female V-shaped iron 6 causing the latter to wipe against and fit 40 the parts of the upper closely around the apex of form 5.

In order to heat the iron 6 I construct the latter with electric heaters 21, 21 adapted to be connected with a source of electric current by wires 22.

After permitting the form 5 to remain within the iron 6 the necessary or desired length of time, the operator removes his foot from the treadle and spring 20 restores the 50 form 5 to its lowermost position again.

When the top and lining are removed from the machine, they are positioned relatively and shaped practically the same, particularly at the rear of the upper, as when 55 the shoe is completed so that in the completed shoe both the lining and outside of the top are smooth and free of wrinkles or other distortions.

The member 5 is made as a hollow casting. The outer inclined walls of which are made with air ducts or ports 23 as shown in Figures 4 and 5. At one end the interior compartment of form 5 is connected by a flexible hose 24 with the inlet of a blower or 65 air pump 25 and when the machine is in use

this air pump or blower 25 is continuously in operation and acts to exhaust the air from the interior of form 5. It will therefore be clear that when the lining is placed in position upon form 5 it is held in position thereon against accidental displacement by air pressure. As shown in Figure 6 the V-shaped recess 26 of presser member 6 is made of such depth or shape that the side walls of this recess contact with the upper 70 upon form 5 before the bottom of the recess 75 engages the upper, thereby preventing contact of the presser member 6 with the back seam or back stay and avoiding undue or injurious pressure upon the latter.

What I claim is:

1. A machine for use in assembling the parts of uppers comprising a frame; an upper supporting and shaping member moveably mounted upon said frame made 85 with rigid work engaging surfaces; an upper stretching and pressing member mounted upon said frame made with rigid work engaging surfaces, and means for moving said first mentioned members toward and from 90 the other member.

2. A machine for use in assembling the parts of uppers comprising a frame; an upper supporting and shaping member moveably mounted upon said frame; an upper stretching and pressing member mounted on 95 said frame in position to co-operate with said first member; means for heating said stretching and pressing member; means for moving said first mentioned member toward 100 and from said stretching and pressing member, and pneumatic means for holding the work in position upon said first mentioned member.

3. A machine for use in assembling the 105 parts of uppers comprising a frame; an upper supporting and shaping member moveably mounted on said frame having substantially the shape of an inverted V an upper stretching and pressing member 110 mounted on said frame above said first member made with a V-shaped recess to receive the top portion of said first member, and means for operating the form member to force the middle portion of the upper into 115 the recess of the presser member.

4. A machine for use in assembling parts of uppers comprising a frame; an upper supporting and shaping member moveably mounted on said frame having substantially the shape of an inverted V and an upper stretching and pressing member mounted on said frame above said first member made with a V-shaped recess to receive the top portion of said first member 120 together with the middle portion of an upper mounted upon the latter and to engage the upper at each side of the back seam or back stay without engaging the latter, and means for moving one of said 125 130

members toward and from the other member.

5. A machine for use in assembling the parts of uppers comprising a frame; a hollow upper supporting and shaping member movably mounted on said frame having the shape of an inverted V and made with rigid work engaging surfaces, the outside walls of said member being formed each 10 with a multiplicity of air ducts, an upper stretching and pressing member mounted on said frame above said first member made with a recess to receive the top portion of the form member and having rigid work engaging surfaces; means for exhausting the 15 air from the interior of said first member, and means for moving one of said members toward and from the other member, said stretching and pressing member engaging only the opposite side portions of the upper 20 on said first member.

In testimony whereof I have affixed my signature.

ALFRED W. DONOVAN.
